UNITED STATES PATENT OFFICE.

HENRY F. SCHULTE, OF HOPEDALE, ILLINOIS.

TOBACCO-PIPE.

976,936.

Specification of Letters Patent. Patented Nov. 29, 1910.

Application filed March 16, 1910. Serial No. 549,707.

To all whom it may concern:

Be it known that I, HENRY F. SCHULTE, a citizen of the United States, residing at Hopedale, in the county of Tazewell and State of Illinois, have invented new and useful Improvements in Tobacco-Pipes, of which the following is a specification.

This invention relates to improvements in tobacco pipes and more particularly to that 10 class of tobacco pipes known as cigar pipes.

One object of the invention is the provision of a cigar pipe provided with a tobacco holding casing to receive the tobacco holder, the said casing being so constructed that 15 sufficient air will be permitted to be drawn to the burning tobacco without the danger of the tobacco escaping from the holder.

Another object is the provision of a tobacco holder provided with an asbestos coil 20 positioned adjacent to the mouthpiece or bit of the holder, whereby the smoke will pass through the convolutions of the coil, thus preventing the tobacco from being drawn through the bit and into the mouth of the 25 smoker, the said coil being to a great extent absorbent, thus extracting a considerable portion of the nicotine from the smoke as it passes therethrough.

With these and other objects in view, 30 which will more fully hereinafter appear, the present invention consists in certain novel details of construction and arrangement of parts, hereinafter fully described, illustrated in the accompanying drawings and more particularly pointed out in the appended 35 claims; it being understood that various changes in the form, proportion, size, and minor details of the device may be made, within the scope of the appended 40 claims, without departing from the spirit or sacrificing any of the advantages of the invention.

In the accompanying drawings, forming a 45 part of the specification;—Figure 1 is a side elevation of the device. Fig. 2 is a longitudinal sectional view thereof.

Similar numerals of reference are employed to designate corresponding parts throughout.

50 The casing is designated by the numeral 5 and conforms to the configuration of one end portion of a cigar. The casing is provided with an axial bore 6 extending from its larger end to the intermediate portion of 55 the casing. When the tobacco holder about to be described is positioned in the casing

communication with the atmosphere is established by means of a pair of air ducts 7 and 8. Reference to the drawings discloses the fact that the air duct 7 extends transverse the casing and is located between the inner end of the bore and closed end of the casing, while the air duct 8 is arranged perpendicular to the duct 7 and communicates at one end with the inner end of the bore and at the opposite end with the medial portion of the air duct 7, it being understood that the air ducts are considerably less in diameter than the diameter of the bore 6.

The tobacco holder is designated in general by the numeral 9 and comprises a cylindrical portion 10 of a diameter to snugly fit within the bore 6, the said cylindrical portion corresponding in length to the length of the bore, or substantially so. The outer 75 end of the cylindrical portion is provided with a shoulder 11 corresponding in diameter to the diameter of the open end of the casing and forming an abutting surface to limit the inward movement of the tobacco 80 holder. That portion of the tobacco holder extending rearwardly from the shoulder is tapered to conform to the configuration of one end of a cigar. The tobacco holder is provided with an axial bore 12 extending 85 from the end of the cylindrical portion to a point a trifle beyond the shoulder 11 and formed in the rear or outer end of the tobacco holder is a longitudinal opening 13 in axial alinement with but considerably less 90 in diameter than the diameter of the bore 12. The opening 13 receives the mouthpiece or bit 14.

The bore 12 of the tobacco holder is provided with a lining of asbestos designated 95 by the numeral 15 and positioned at the inner end of the bore is a coil of asbestos designated by the numeral 16. The coil is of such diameter that it tightly fits within the holder and provides a base for the tobacco, while the spaces between the convolutions of the coil are sufficient to permit the smoker to draw the smoke of the tobacco therethrough. By the provision of the coil it will be observed that a filter is 100 provided owing to the asbestos coil being to a great degree absorbent, thus taking a greater portion of the nicotine from the smoke as it passes therethrough.

In the use of the device the cylindrical portion of the holder is filled with tobacco 110 and lighted, after which the said cylindrical

portion is inserted into the bore 6 of the casing, whereupon the smoking operation may be performed in the usual manner.

From the foregoing, it is evident that I have provided a device which is comparatively simple in structure and inexpensive in manufacture, embodying few parts and these so arranged that the danger of derangement will be reduced to a minimum.

10. I claim:—

1. A cigar pipe comprising a casing provided with an axial bore extending from one end to the medial portion of the casing, and further provided with a pair of air conduits arranged at right angles to each other, one of said conduits extending transverse the casing at a point between the inner end of the bore and closed end of the casing, and the other of said conduits extending longitudinally of the casing having one end communicating with the inner end of the bore and its opposite end leading into the transverse conduit, and a tubular tobacco holder telescoping into the bore of said casing.

2. In a cigar pipe comprising a casing provided with an axial bore extending from one end to the medial portion of the casing, and further provided with a pair of air conduits of less diameter than the bore and arranged at right angles to each other, one

of said conduits extending transverse the casing at a point between the inner end of the bore and closed end of the casing, and the other of said conduits extending longitudinally of the casing having one end communicating with the inner end of the bore and its opposite end leading into the transverse conduit, and a tubular tobacco holder telescoping into the bore of said casing.

3. A cigar pipe comprising a casing provided with an axial bore and an air conduit leading from the outer end of the casing to the inner end of the bore, a tubular tobacco holder having a cylindrical end portion to slidingly fit in the bore of the casing and provided at its opposite end with a bit, said cylindrical portion being provided with an axial bore extending from one end to a point adjacent the opposite end and terminating in a reduced longitudinal opening to receive a mouthpiece, a lining of asbestos positioned on the inner surface of said cylindrical portion, and an asbestos coil positioned at the base of the bore of said holder, for the purposes described.

In testimony whereof I affix my signature in presence of two witnesses.

HENRY F. SCHULTE.
